Attorney, Agent, or Firm—Collard & Roe***[57] ABSTRACT**

A book comprises a plurality of sheets, each sheet being folded in a zone constituting a back of the book to provide two leaves, at least one first sheet having one of the leaves thereof arranged between the two leaves of a second sheet and the other leaf thereof arranged between the two leaves of a third sheet.

5 Claims, 3 Drawing SheetsFIG. 1

FIG. 2

FIG. 3

FIG. 4

BOOK

BACKGROUND OF THE INVENTION

1. Field of the Invention

The invention relates to a book with a plurality of sheets each comprising two leaves which are folded in the zone of the book back.

2. Description of the Prior Art

Books are known which consist of a plurality of leaves which are sown or glued together at the book back. The term "book" as stated hereinunder shall mean a product comprising a plurality of leaves connected to each other, which also includes booklets, brochures and the like. In known books it is often the case that two leaves form a sheet which is folded in the center. Often several such sheets are stuck within each other, so that the first and the last leaf of a book belong to one sheet, the second and one but last leaf belong to the next sheet and so forth. In order to ensure the cohesion it is necessary to either glue or sow them together. This is expensive and thus limits the possible number of pages in a book. It is possible that a book is compiled from several such partial books, but this solution is also very difficult to achieve.

From the German Patent 682 075 (SCHWENKE) a book is known whose pages are provided with laps which are inserted into respective cut-outs in the cover sheet. In order to ensure coherence, the laps have to be glued.

SUMMARY OF THE INVENTION

It is the object of the present invention to avoid such disadvantages and to create a book which requires no gluing or sowing and which can have an unlimited number of pages.

In accordance with the invention it is therefore provided that at least one sheet is provided whose one leaf is arranged between the two leaves of a further first sheet and whose second leaf is arranged between the two leaves of a second further sheet. The individual sheets interdigitate like the links of a chain. An additional connecting means is not necessary.

Preferably, a first group of sheets is provided, each comprising two cut-outs extending from two opposite edges towards the center of the sheet, and a further group of sheets is provided which comprises in the center a slot-shaped cut-out, each sheet of the first group being insertable into the cut-out of a respective sheet of the second group. When compiling the book, the sheet with the two cut-outs is folded and inserted into the center cut-out.

The production of a book in accordance with the invention is facilitated if a plurality of leaves of other sheets are arranged between the two leaves of a sheet.

An appealing arrangement is achieved if the two outermost leaves each belong to sheets of the second group with a cut-out in the center.

It is particularly advantageous if the cut-outs of the second group of the sheets have the shape of an elongated oval. The individual sheets center themselves by this measure.

BRIEF DESCRIPTION OF THE DRAWING

The invention is now outlined in greater detail by reference to the enclosed drawings, in which:

FIG. 1 shows a sheet with two cut-outs;
FIG. 2 shows a sheet with a slot-shaped cut-out and
FIGS. 3 and 4 schematically show two embodiments
of a book in accordance with the invention.

DESCRIPTION OF THE PREFERRED
EMBODIMENTS

The sheet 1 shown in FIG. 1 comprises two cut-outs 3 and 4 extending along the axis of symmetry 5 of sheet

10 1. The cut-outs 3 and 4 start in the center of the edges 6 and 7 of sheet 1 and have lengths l_1 and l_2 . The axis of symmetry 5 divides sheet 1 into leaves 1' and 1".

The sheet 2 shown in FIG. 2 comprises a slot-shaped cut-out 8 extending along the axis of symmetry 9. The

15 cut-out 8 has a substantially oval shape and a length l_3 . The total of lengths l_1 and l_2 of cut-outs 3 and 4 and the length l_3 of the slot-shaped cut-out 8 has to be equal to or slightly greater than the length L of the edges 10 or 11 of sheets 1 or 2 which are parallel to the axis of symmetry 5 or 9. The axis of symmetry 9 divides the sheet 2 into leaves 2' and 2".

20 FIG. 3 shows the minimum arrangement of a book in accordance with the invention. A sheet 1a, folded along the axis of symmetry 5 shown in a broken line, holds the sheets 2a and 2b extending respectively along leaves 1a' and 1a" of sheet 1a. Leaf 1a' is inserted between the leaves 2a' and 2a" of sheet 2a and the leaf 1a" of sheet 1a is inserted between the leaves 2b' and 2b" of sheet 2b.

25 FIG. 4 shows the manner in which it is possible to produce a book of arbitrary thickness. The leaves 1c' and 1d' of sheets 1c and 1d are arranged between the leaves 2c' and 2c" of sheet 2c. The leaves 1c", 1d", 1e' and 1f' of sheets 1c, 1d, 1e, 1f are arranged between the leaves 2d' and 2d" of sheets 2d. Finally, the leaves 1e" and 1f" of sheets 1e and 1f are arranged between the sheets 2e' and 2e" of sheet 2e.

30 It is clear that the present invention is not limited to books, booklets and the like with rectangular leaves of even size.

35 40 I claim:

1. A book comprising a plurality of sheets, each sheet being folded in a zone constituting a back of the book along an axis of symmetry extending between two opposite edges of the sheets to provide a first leaf and a second leaf, at least one first one of the sheets having the first leaf thereof arranged between the two leaves of a second one of the sheets and the second leaf thereof arranged between the two leaves of a third one of the sheets, the first sheet having two cut-outs extending 45 along the axis of symmetry from the opposite edges towards the center, and the second and third sheets having a slot-shaped cut-out extending along the axis of symmetry in the center, the leaves of the first sheet being insertable into the slot-shaped cut-outs in the second and third sheets.

50 55 2. The book of claim 1, comprising a first group of sheets comprised of the first sheets and a second group of sheets comprised of the second and third sheets.

3. The book of claim 2, comprising two outermost leaves belonging to the sheets of the second group.

4. The book of claim 1, comprising a plurality of said first sheets having the first leaves thereof arranged between the two leaves of the second sheets and the second leaves thereof arranged between the two leaves of the third sheets.

5. The book of claim 1, wherein the slot-shaped cut-outs are oval.
